CLAIM

The ornamental design for a pitcher and lid therefor, as shown.

DESCRIPTION

FIG. 1 is a general perspective view of the pitcher and lid embodying the present invention;

FIG. 2 is a top plan view of the pitcher and lid shown in FIG. 1;

FIG. 3 is a right side elevational view of the pitcher and lid shown in FIG. 1;

FIG. 4 is a bottom plan view of the pitcher and lid shown in FIG. 1;

FIG. 5 is an exploded perspective view of the pitcher and lid shown in FIG. 1; and,

FIG. 6 is an exploded rear elevational view of the pitcher and lid shown in FIG. 1.

*FIG. 1**FIG. 2*

FIG. 3

FIG. 4

FIG. 5

FIG. 6
